ANTIJAMMING MEANS FOR MULTIPLE-COIN FARE COLLECTING APPARATUS

Max L. Grant, Providence, R. I.

Application May 22, 1951, Serial No. 227,636

4 Claims. (Cl. 133—1)

1

This invention pertains to fare collecting apparatus such, for example, as is employed in the buses of public transportation systems or the like.

In the most recent apparatus of this type, provision is made for receiving a fare which is deposited by the passenger himself; for clearly exhibiting the fare to the passenger and to the bus driver as the fare moves through the apparatus; for gauging the individual coins or tokens constituting the fare to determine their denominations; for counting and registering the individual fare and totaling the fares received; for assorting the coins or tokens after they have been counted; and for delivering the coins or tokens, according to their respective denominations, into corresponding magazine tubes of a coin carrier or changer. Not until the coins have been counted and assorted is it possible for the bus driver to take them into his hand. After they have been counted and assorted, he is responsible for the delivery to his employer of an amount of money corresponding to that indicated by the fare register as having been deposited. Thus, in theory, it is impossible for the bus driver to short-change his employer.

However, some bus drivers refuse to be defeated in their desire to appropriate some of the fare money to their own use, and being aware of the fact that, if the fare collecting apparatus become inoperative during a trip, the fare must then be collected by hand with no mechanical check of the amount received, try to devise some way of jamming the mechanism to provide an excuse for hand collection. The introduction of bent or otherwise imperfect coins or slugs, or coins coated with gum or wax, has, in the past, been a favorite expedient, but this scheme has now been defeated by the provision of scavenger devices in the apparatus so arranged that a jammed coin may readily be freed by the driver so that the mechanism may resume its normal operation. Another practice, and one which accounts for by far the greater number of instances of jammed mechanism, is that of allowing coins to continue to pile up in the magazine tubes of the coin changer until there is no room for further coins to pass down from the assorting mechanism. Thus, the latter is clogged and the machine must be disassembled to clear it before it will again operate. It has been proposed to discourage this latter practice by providing space through which coins overflowing the tops of the magazine tubes of the coin changer, may fall into a suitable receptacle arranged

2

such a receptacle may become filled to overflowing. It has also been proposed to provide a transparent panel or window immediately above the coin changing device through which an accumulation of such coins may readily be seen, thus nullifying the excuse that the driver did not realize that the magazines were full. While these several expedients are desirable and useful and in most cases effective, instances still occur, by reason of carelessness or by malicious intent, of the piling up of coins above the coin changer with resultant jamming of the apparatus. The principal object of the present invention is to provide a further improvement, either adjunctive to previous devices having the same general purposes or as an alternative thereto, whereby overloading of the coin changing device and consequent jamming of the magazine is prevented. In the accomplishment of this object the present invention provides an escape port from the space immediately above the coin changer so devised that although coins normally drop into the magazine tubes of the coin changer without danger of escape, any surplus coins which pile up in this space and which, except for the provision of the port might cause jamming of the assorting mechanism, will fall freely out of the machine and onto the floor of the bus. Since these coins have already been counted and registered, and thus must be accounted for by the bus driver, the novel arrangement of the present invention provides a very effective safeguard against careless or wilful failure to clear coins from the coin changer before the accumulation becomes great enough to cause damage.

A further object is to provide means whereby coins may be manually loaded into the magazine tubes of the coin changer more expeditiously than in the usual apparatus, for example, when it is desired at the start of a run to load the magazine tubes with coins. The port provided for the escape of coins, as above referred to, has the secondary purpose of providing a free passage through which coins, several at a time, may be introduced into the coin changer, as contrasted with prior practice in which narrow slots, through which one coin at a time could be introduced, were the only available way of dropping coins manually into the magazine tube. Other and further objects and advantages of the invention will be pointed out in the following more detailed description and by reference to the accompanying drawings wherein

Fig. 1 is a fragmentary front elevation of the lower portion of coin-collecting apparatus of a

recent type and which is widely used, showing the coin changer in position and the escape port opening from the space immediately above the changer through which coins may fall out of the machine; and

Fig. 2 is a fragmentary, vertical section, to larger scale, on the line 2—2 of Fig. 1, showing the internal structure and the manner in which surplus coins may escape.

Referring to the drawings, the numeral 1 designates the outer casing of a fare collecting machine of the type above referred to and such as is more fully illustrated, for example, in the co-pending application for Letters Patent Serial No. 216,703, filed March 21, 1951, by Miller. The 15 details of the coin-receiving, gauging, counting and assorting mechanism embodied in such a machine form no part of the present invention and are not herein further described. It suffices to note that the upper part of the case has a 20 downwardly and forwardly transparent panel 2 through which the coins forming the fare may be observed, and that at approximately the point 3 the assorting mechanism is located. Such 25 assorting mechanism separates the coins or tokens constituting the deposited fare according to denomination and delivers the coins of each respective denomination into a coin diverter or guide 4 having partitions 5, 5^a, 5^b, etc. which, with its end walls, define separate guideways or compartments for coins of different denominations. This diverter or guide is usually a casting, open at its front, and having a flaring upper portion forming a sort of hopper to receive the coins as they drop down from the assorting mechanism. Each of the guideways of the diverter has a delivery aperture in its floor through which the coins which fall into said guideway may drop freely. The rear wall of the diverter terminates at an upper edge 6. It has heretofore been proposed to provide an overflow receptacle, within the casing of the apparatus and to the rear of the diverter, into which coins which might, on occasion, pile up within the diverter guideways, may fall, thereby to avoid the piling up of coins above the diverter. However, this expedient has not always proven sufficient to avoid jamming of the assorting mechanism, as hereinafter explained.

The fronts of the several guideways or compartments of the diverter 4 are formed by a door or panel 7 which normally fills the major portion of a transversely elongate aperture 7^a in the front wall of the casing. This door is transparent so as to expose to view any coins which accumulate within the diverter compartments. This door is hinged at its lower edge at 8, and springs 9 tend to hold the door in closed position. However, the door may be swung forwardly and downwardly by hand to permit coins to be discharged from the diverter compartments if it is desired to do so.

Below the edge of the diverter 4, the casing of the apparatus has a chamber 10 (open at the front) for the reception of a removable coin changer device 11 comprising a plurality of vertical magazine tubes 12, 12^a, 12^b, etc., each providing a chamber designed to receive coins of a given denomination. Each of these magazine tubes is arranged below one of the delivery apertures (for example, the aperture 13) in the floor of the respective compartments of the coin diverter, and each magazine tube is provided with means (which may be conventional) for delivering a predetermined number of coins at a time 75

from the tube into the hand of the operator. This removable coin changer is normally held within the chamber 10 by a retaining bar 14 which is normally locked in place, but which may be released to permit removal of the coin changer from the apparatus.

As above described, the door 1 occupies the lower major portion of the aperture 7^a in the front wall of the case 1, but the upper edge 15 (Fig. 1) of this door is spaced below the upper edge 16 of the aperture to provide a space of a vertical width substantially exceeding the thickness of any of the coins or tokens which are employed, and preferably exceeding the thickness of two or more such coins piled on the other. This space, between the top edge of the door and the edge of the aperture, constitutes an escape port P through which coins may fall forwardly out of the apparatus and onto the floor.

Normally the coins, for example, the coin C (Fig. 2), falls down from the assorting mechanism and into one of the guideways or compartments of the diverter 4, and then drops down into one of the magazine chambers of the coin changer. If the operator is properly observant of conditions, he will note the height of the stack of coins in the tubes 12, 12^a, etc., (this being made possible by the provision of slots or apertures 17 in the front walls of the tubes) and will withdraw coins from the tubes, as required, to prevent them from overflowing. However, at times coins may pile up in one or another of the magazine tubes and into the corresponding compartments of the diverter 4 as indicated, for example at C' (Fig. 2). The accumulation of coins in the diverter is easily observable through the transparent door 7 and should be sufficient to warn the operator of the desirability of withdrawing coins. However, if the operator pays no attention to this condition until the compartments in the diverter are completely full, coins then dropping down from the assorting mechanism will slide down off of the coins filling the diverter compartments and out through the port P and will fall onto the floor. This effectively prevents coins from piling up within the diverter compartments to a height such as to cause jamming of the assorting mechanism. Since the operator is accountable for all coins which have passed through the counting and assorting mechanism, the dropping of coins onto the floor, with possibility of attendant loss, provides a very powerful incentive to induce the operator to watch the apparatus and to withdraw coins from the coin changer at sufficiently frequent intervals to prevent a damaging accumulation of coins in the diverter.

While, as above noted, it has heretofore been proposed to provide a receptacle, within the case of the apparatus, at the rear of the coin changer into which surplus coins from the diverter might fall, such an arrangement has not been found altogether adequate because the coins which fall into such receptacle are not lost, and because, if the condition continue long enough, such overflow receptacle will itself be completely filled and thereafter coins may pile up to an extent sufficient to jam the assorting mechanism. With the arrangement of the present invention, the escape port of coins from the apparatus completely avoids the possibility of undue accumulation, and the attendant possibility of loss is an adequate safeguard against the purposeful or careless failure of the operator to withdraw coins at the proper

Further, the provision of the large port P, through which a plurality of coins may be introduced at the same time, by hand, greatly facilitates the deposit of coins in the coin changer tubes as is necessary at the start of a run, or when, at other times, a given tube has become depleted. Heretofore the only way of introducing coins manually into the coin changer tubes was by dropping them one at a time through narrow slots 18 provided in the front wall of the case just above the coin diverter which is slow and troublesome.

While one desirable embodiment of the invention has herein been disclosed by way of example, it is to be understood that the invention is broadly inclusive of any and all modifications falling within the scope of the appended claims.

I claim:

1. In apparatus of the class described wherein a casing houses mechanism for assorting the coins, which constitute a multiple-coin fare, according to denomination, the coins then being delivered into corresponding chambers of a magazine, in combination, a fixed coin guide within the casing interposed between the assorting means and the magazine, said coin guide having walls which define separate guideways which are registered with the several magazine chambers and through which the coins pass on their way from the assorting means to the magazine, the casing comprising a movable, but normally stationary, panel forming a portion, at least, of the front wall of each of the several guideways, said panel being normally closed but movable to afford free access to the guideways, the panel being of less height than the guideways, there being a freely open port above the panel through which coins, attempting to enter the guideways, after the latter are substantially full, may escape and fall forwardly out of the casing.

2. In apparatus of the class described wherein a casing houses mechanism for assorting the coins, which constitute a multiple-coin fare, according to denomination, the coins then being delivered into corresponding chambers of a change maker, removable as a unit from the casing in combination, a coin guide within the casing and interposed between the assorting means and the magazine, said coin guide having stationary walls which define separate guideways which are registered with the several magazine chambers and through which the coins pass on their way from the assorting means to the magazine, the casing, at its front, having a transparent panel which forms a part, at least, of the front wall of each of the several guideways, said panel being hinged at its lower edge, and means normally holding the panel in closed position, the panel being of less height than the guideways, there being a freely open port whose lower edge is defined by the upper edge of the panel, through which coins, attempting to enter the guideways, after the latter are substantially full, may fall forwardly out of the casing.

3. In apparatus of the class described wherein

a casing which houses mechanism for assorting the coins, constituting a multiple-coin fare, according to denomination, the coins then being delivered into corresponding chambers of a change maker, removable as a unit from the casing, a coin diverter within the casing, interposed between the assorting means and the magazine, said diverter having stationary walls which define guideways registering with the several magazine chambers through which the coins pass on their way from the assorting means to the magazine, the front of the casing comprising part which defines the front wall of the several diverter guideways said part having therein an aperture which extends from a point near the bottoms of said guideways to a point near their tops, and a transparent panel which normally fills the major part of said aperture, the height of the panel being less than that of the aperture, thereby providing an escape port above the panel through which coins, attempting to enter the diverter guideways, after the latter are nearly full, may fall forwardly out of the casing.

4. In apparatus of the class described wherein a casing which houses mechanism for assorting the coins, constituting a multiple-coin fare, according to denomination, the coins then being delivered into corresponding chambers of a change maker, removable as a unit from the casing, a stationary coin diverter within the casing interposed between the assorting means and the magazine, said diverter having fixed walls which define guideways registering with the several magazine chambers through which the coins pass on their way from the assorting means to the magazine, the front of the casing comprising a part which defines the front wall of the several diverter guideways, said part having therein an aperture which extends transversely across the several guideways and from a point near their bottoms to a point near their tops, and a panel which normally fills the major portion of the aperture, hinge means connecting the lower edge of the panel to said wall-forming part, and spring means normally holding the panel in closed position, the panel being of less height than the aperture, thereby leaving the upper portion of the aperture open to constitute an escape port through which coins, attempting to enter the diverter guideways, after the latter are nearly full, may fall forwardly out of the casing.
